(57) **CLAIM**

The ornamental design for a disposable aluminum cooking pan for grill, etc., as shown and described.

DESCRIPTION

FIG. 1 is a perspective view of a disposable aluminum cooking pan for grill, etc., showing my new design;

FIG. 2 is a front elevational view of the invention; the rear elevational view being mirror image thereof;

FIG. 3 is a left-side elevational view of the invention, the right-side elevational view being a mirror image thereof; and, FIG. 4 is a top plan view of the invention, the bottom plan view being a mirror image thereof.
